UNITED STATES PATENT OFFICE.

ELMER A. LONGDON, OF BRIDGEPORT, CONNECTICUT.

MANUFACTURE OF SHEARS.

SPECIFICATION forming part of Letters Patent No. 246,165, dated August 23, 1881.

Application filed January 7, 1881. (No model.)

To all whom it may concern:

Be it known that I, ELMER A. LONGDON, of Bridgeport, Fairfield county, Connecticut, have invented certain Improvements in the Manufacture of Shears, of which the following is the specification.

The object of my invention is to produce scissors of greater strength and less liability to defacement than those heretofore made; and this 10 I effect by constructing them in the manner hereinafter described, and illustrated in the accompanying drawings, in which—

Figure 1 is an edge view, showing the detached parts constructed in the ordinary manner to form a scissors-section, one blade being 15 in part section. Fig. 2 is a plan showing such section completed; Fig. 3, a view showing the forms of sections used in my improved mode of manufacture; Fig. 4, a plan of the handle-section; Fig. 5, a plan of the blade-section.

The ordinary mode of constructing scissors consists in forming the cast-iron handle A, Fig. 1, with a flat projection, *a*, and lug *c*, and the steel blade B with a hole, *e*, to receive the lug, 25 the end of the handle overlying the inner end of the blade, to which it is secured by welding. The section thus made, when formed, grooved, and finished in the ordinary manner, presents a polished surface extending from the point *x* 30 to the end *y*, and a shoulder, *z*, at the point where the cast-iron handle terminates, said shoulder resulting from the beveling of the blade in forming the cutting-edge *i*. As a result of this mode of manufacturing, the weld 35 is formed at the weakest portion, *z*; but the main objection is that the exposed polished surface is partly upon the cast-iron and partly upon the steel portion of the article, so that when subjected to moisture or fumes the portion be-

40 tween the point *z* and the japanned or coated portion of the handle A will quickly tarnish and become rusty, the remainder of the blade retaining the polish.

The imperfect welding of the metals at the 45 point *z*, where the handle terminates over the blade, is apt to form seams and scars upon the upper face, which mar the appearance of the

article. I overcome these objections by constructing the handle portion A, Fig. 3, with a flat projection, *d*, having a shoulder, *s*, which, 50 with said projection, forms a sunken portion adapted to receive the end of the blade B, which end is reduced in thickness and extends back to the shoulder *s*, or as far as the blade is polished, and I form the lug *c* on the under side of 55 the blade to fit a hole, *e*, in the handle. When the blade is welded to the handle the junction at the shoulder *s* is concealed, however imperfect the weld may be, while the shoulder *z*, being in the body of the steel, and not at a point 60 of union of the sections, is less apt to detract from the strength of the article. One of the main advantages, however, is that the entire finished and polished portion of the article is of steel, (no iron being exposed.) Consequently 65 the brightness and luster of the metal is preserved wherever the same is uncoated.

I am aware that it has been common to cast the handle directly upon the steel blade with part of the cast portion overlying the steel; 70 but this mode of manufacture is not adapted to the quality of articles that I make, nor does it result in forming the whole exposed surface of steel. So, also, a tongue at the end of the steel blade has been let into a recess in the iron 75 handle; but in such case a portion of the handle is exposed and will tarnish, as will also the iron rivets heretofore used for riveting the overlying steel blade to the iron handle. I do not claim any of the above-named features; but 80

I claim—

The combination, in a scissors-section, of a steel blade, B, with a lug, *c*, at its rear end, and a cast-metal handle, A, formed with a shoulder, *s*, tongue *d*, and perforation *e*, riveted and 85 welded together with the end of the steel blade abutting against the shoulder *s*, as set forth.

In testimony whereof I have signed my name to this specification in the presence of two subscribing witnesses.

ELMER A. LONGDON.
